UNITED STATES PATENT OFFICE

JUNIUS M. SCHUTTE, OF CHICAGO, ILLINOIS, ASSIGNOR TO THE AERO MODEL COMPANY, OF CHICAGO, ILLINOIS, A CORPORATION OF ILLINOIS

DESIGN FOR AN AERIAL TOY

Application filed February 16, 1931. Serial No. 38,674. Term of patent 7 years.

To all whom it may concern:

Be it known that I, JUNIUS M. SCHUTTE, a citizen of the United States, residing at Chicago, in the county of Cook and State of Illinois, have invented a new, original, and ornamental Design for Aerial Toy, of which the following is a specification, reference being had to the accompanying drawings, forming a part thereof.

Figure 1 is a top plan view of the toy; and Figure 2 is a side view of the toy as it would appear in flight.

I claim:

The ornamental design for an aerial toy, substantially as shown.
